MOBILE LOUDSPEAKER TOY

Isaac Heller, Maplewood, N. J., assignor to Robin Hood
Co., Newark, N. J., a corporation of New Jersey

Application August 1, 1955, Serial No. 37,245

Term of patent 14 years

(Cl. D34—15)

I claim:

The ornamental design for a mobile loudspeaker toy, as shown.
